ELEMENT ASSEMBLY FOR ELECTRON
DEVICESWalter Louis Krahl, Montclair, N. J., assignor, by
mesne assignments, to Arcturus Development
Company, a corporation of Delaware

Application May 6, 1930, Serial No. 450,075

7 Claims. (Cl. 250—27.5)

This invention relates to electron devices and particularly to a means and a method for assembling the electrodes in such devices and is a modification of the construction shown in my 5 patent entitled "Unitary element structure for vacuum tubes", Patent No. 1,857,647, dated May 10, 1932, and is a continuation in part of my Patent No. 1,869,568, dated August 2, 1932.

One of the objects of the invention is to provide 10 a unitary element structure for an electron device which may be assembled entirely independently of the press upon which it is adapted to be supported.

Another object of the invention is to provide 15 a rigid element structure for an electron device in which there is little or no possibility of the elements getting out of alignment even under extreme conditions of shock or vibration.

Another object of the invention is to provide 20 a novel means for mounting the filament in an electron device.

Another object of the invention is to provide a unitary element structure for an electron device which may be supported upon the electrical 25 connectors, therefore, the connectors for each element helping to increase the rigidity of the whole unit.

A still further object of the device is to provide 30 a unitary element structure for an electron device which may be supported upon straight, parallel support rods of predetermined lengths.

Still another object of the invention is to provide 35 a clip for supporting the end of the filament in an electron device.

Other objects and objects relating to the means 40 and method of manufacturing and assembling the various parts will be apparent as the description of the invention proceeds.

Several embodiments of the invention have 45 been illustrated in the accompanying drawings, in which:

Fig. 1 is a front elevation of an electron device embodying the invention with portions removed for clearness;

Fig. 1^a is a perspective view of the lower insulator;

Fig. 2 is a sectional plan view of the elements taken on the line 2—2 of Fig. 1;

Fig. 3 is an enlarged sectional front view of 50 the lower portion of the element structure illustrating the method of attaching the filament;

Fig. 4 is a sectional side view through a portion of the element structure taken on the line 4—4 of Fig. 3;

Fig. 5 is a front elevational view of another 55

embodiment of the invention with portions removed for clearness;

Fig. 6 is a sectional side view of the element structure taken on the line 6—6 of Fig. 5;

Fig. 7 is a plan view of the element structure 5 of Fig. 5;

Fig. 8 is a sectional plan view of the element structure taken on the line 8—8 of Fig. 5;

Fig. 9 is a sectional plan view of the yokes for supporting the element structure taken on the line 9—9 of Fig. 5;

Fig. 10 is a front elevation of another embodiment of the invention with portions removed for clearness;

Fig. 11 is a plan view of the element structure 15 of Fig. 10;

Fig. 12 is a sectional plan view of the element structure of Fig. 10 taken on the line 12—12 of that figure;

Fig. 13 is a sectional plan view showing the 20 yoke structure of Fig. 10 and taken on the line 13—13 of that figure;

Fig. 14 is a sectional plan view of the lower part of the yoke structure taken on the line 14—14 of Fig. 10;

Fig. 15 is a perspective view of the lower insulator of Fig. 10;

Fig. 16 is a sectional side view of the insulator showing the filament attaching clip and taken on the line 16—16 of Fig. 15;

Fig. 17 is a perspective view of a modified form 30 of insulator showing a different type of attaching clips for the filament;

Fig. 18 is a sectional side view of a portion of the insulator of Fig. 17 taken on the line 18—18 35 of that figure;

Fig. 19 is a front elevation of still another embodiment of the invention, certain parts being removed for clearness;

Fig. 20 is a sectional side view of the element 40 structure of Fig. 19 taken on the line 20—20 of that figure;

Fig. 21 is a sectional plan view taken on the line 21—21 of Fig. 19; and

Fig. 22 is a perspective view of the means for 45 attaching the lower ends of the filament in Fig. 19.

Referring more specifically to Fig. 1, the invention is illustrated in connection with an electron device having an envelope 1 of glass or 50 other desirable material mounted upon the usual base 2 of insulating material such as bakelite or hard rubber which supports the terminals for making the necessary connections to the device. A stem tube 3 is formed integral with the en- 55

velope 1 and is positioned upright within the envelope terminating in the press 4 in which the element supporting posts are sealed providing the means for making the electrical connections to 5 the elements from the outside of the tube.

The elements of the tube comprise an anode 5, a grid 6, and a filamentary cathode 7. Both the anode and the grid may be formed of a flattened cylinder while the filament may comprise two V-shaped filaments connected in series 10 and forming a single filament having the configuration of an M. The anode may be made in two parts, each part having a curved portion 8 terminating at each side in flanges 9 which may 15 be provided at their extreme edges with grooves 10 adapted to cooperate when the anode parts are placed together to form sockets to receive supporting posts in a manner to be hereinafter described. When the flanges 9 of the two co- 20 operating portions are secured together as by forcing portions of one through openings in the other, the portions being bent back over the opposite side of the flange, a complete anode structure is provided.

25 The anode structure may have a flat insulating plate 11 attached to it at the upper end and another flat insulating plate 12 attached at the lower end. To this end I provide extensions on each of the flanges 9 with fingers 13 at the ends 30 thereof which are adapted to extend through openings 14 in the insulating plates 11 and 12 and be bent over on the reverse side to hold the plates firmly in place at the ends of the anode flanges.

35 The other elements of the tube may be mounted upon the insulating plates 11 and 12 and to this end the grid 6 which comprises the usual helix of wire is wound upon two support rods 16 and 17 which pass through holes 18 and 19 provided in each plate to receive them. The grid 40 is somewhat smaller than the curved portions 8 of the anode but is substantially parallel therewith so that it fits within the anode and the filamentary cathode 7 is positioned within the 45 grid.

In order to support the lower end of the filament the clips 21 are provided upon the lower insulator 12. These clips 21 are spaced apart 50 between the grid support rod holes 18 and 19 and are secured to the insulator. Each of the clips 21 is substantially U-shaped having a flat portion 22 adapted to rest upon the top of the insulator and two legs 23 which are adapted to extend through openings 24 provided in the insulator for that purpose. The flat portion 22 on each clip may be provided with a transverse ridge or depression 26 which provides a place for the filament 7 to pass under the surface 22 of the clip as illustrated in Fig. 4. The legs 23 of 60 each clip 21 are preferably somewhat rounded to fit the top of a supporting post which also makes the necessary electrical connection to the filament and which will be hereinafter described.

65 On the upper plate 11, I provide two openings 27 through which extend pins 28 which are supported by means of coil springs 29 and which have hooks 31 at their lower ends to receive the two loop ends of the filament. These two pins 28 are spaced apart as indicated in Fig. 1. The 70 lower end of the filament is then welded underneath the left hand clip 21, as indicated in Fig. 3, passes up over the left hook 31 on the left hand pin 28, down under the flat portion 22 of the center clip 21, up again over the hook 31 on the 75 right hand pin 28, and down again to be welded

underneath the flat portion 22 of the right hand clip 21. This mounts the M-shaped filament firmly in position within the grid and supports the two loop ends thereof resiliently so as to maintain all straight portions of the filament under tension at all times.

In order to support the unitary element structure upon the press 4, I provide two relatively long support posts 32 sealed in the press at the outer ends thereof which are adapted to pass 10 through holes 33 in the insulators 11 and 12 and through the sockets formed by the grooved edges 10 of the anode flanges 9, these posts forming the principal support for the structure. The flanges 9 may be welded to the supports 32 to 15 increase the rigidity of the construction and make a good electrical contact therewith. Adjacent the posts 32 I provide two additional posts 34 which are somewhat shorter and are bent at an angle at the top where they contact with the 20 lower ends of the grid support posts 16 and 17 and to which they may be welded thereby aiding in maintaining the element structure in position.

25 Adjacent the support posts 34, I provide two additional support posts 36 which are also sealed 30 in the press 4 and extend upwardly and slightly outwardly and terminate at a point flush with the lower surface of the insulator 12. The support posts 36 are bent to align themselves with the two end clips 21, legs of which are rounded 35 to conform to the upper ends of the support rods and may be welded to them thereby increasing the rigidity of the structure. An additional support post 37 may be sealed at the center of the press 4 and may extend upwardly to a point flush 40 with the lower surface of the insulator 12 where it may be aligned with the central clip 21 and welded to the legs 23 thereof to further increase the strength and rigidity of the whole unit.

45 In assembling the construction shown in Fig. 40 1 the filament 7 would first be secured upon the lower insulating plate 12 by means of the clips 21. Thereupon the grid 6 would be placed over the filament with the grid supports 16 and 17 extending through the holes provided for that 45 purpose in the lower insulating plate and the anode would then be placed over the grid with the fingers 13 engaging the lower insulating plate as indicated. Then the upper insulating plate 11 may be applied and the wires 28 may be inserted through the openings 27 in the upper insulating plate to engage the loop ends of the two sections of the filament 7 when they may be drawn up until the filament is taut and then welded to the springs 29. In order to accomplish 55 this the wire 28 may be considerably longer than is necessary and may be cut off above the spring 29.

50 Thus described the element unit is mounted rigidly upon the press 4 and electrical connections may be made therefrom to the terminals at the base of the tube. To this end a wire 38 may be provided connecting one of the support posts 32 with the anode terminal 39 at the base of the tube. A pair of wires 41 may be provided 60 connecting the filament support rods 36 with the filament terminals 42 at the base of the tube while a wire 43 may connect one of the grid support posts 34 with the base terminal 44.

65 It will be evident from the above that I have 70 provided a unitary element structure for an electron device in which all of the parts may be assembled entirely independently of the press of the tube and the unit then mounted upon the press, the several support rods sealed in the press 75

aiding in maintaining the element unit in position and at the same time providing the electrical connections for the element. All of the parts are rigidly supported with respect to the other parts, there being no possibility of any movement with respect to each other so that the parts cannot get out of alignment nor touch each other to interfere in any way with the operation of the device.

In Figs. 5 to 9 inclusive a modification of the invention is shown in which a different means of supporting the filament is illustrated, being somewhat similar to the means shown and described in my above mentioned application. The anode 5 in this construction is similar to that shown in Figs. 1 to 4 as is also the grid 6 which is supported upon the support posts 16 and 17. An insulator 46 is provided at the top of the anode similar to the insulator 11 and held upon the anode by means of the fingers 13 as in the previous case. At the lower end of the anode an insulator 47 is provided which may be held upon the anode similarly to the insulator 46 but has different openings to receive supporting means for the filament.

Both the insulators 46 and 47 are provided with openings 18 and 19 to receive the grid posts 16 and 17. Each of these insulators is also provided with holes 48, 49 and 50 to receive filament support posts 51, 52, and 53 respectively. These filament support posts 48, 49, and 50 are preferably square in cross-section and extend above the insulator 46 and below the lower insulator 47 as clearly shown in Fig. 5. The posts are secured to the upper insulator 46 by means of clips 54 which are bent completely around the insulator and are provided with openings 56 through which the posts extend. The lower ends of the clips 54 are bent downwardly beneath the insulator 46 and extend along the sides of the filament support posts to which they may be welded thus rigidly securing each of the posts 51, 52, and 53 to the upper insulator. The lower ends of these posts extend through the openings 45 in the lower insulator 47 and are freely movable therein so that expansion and contraction of these posts will not be interfered with.

A pair of hairpin filaments 57 and 58 are mounted upon the posts 51, 52, and 53, the filament 57 being secured at its lower ends to the posts 51 and 52, while the filament 58 has its lower ends secured between the posts 52 and 53. To support the upper ends of the filament a plate 59 of insulating material such as mica is provided. This plate rests upon the upper surface of the clips 54 and is provided with openings 61, 62, and 63 to receive the posts 51, 52, and 53 respectively, the openings 61 and 63 being slotted to the end of the insulating plate if desired.

The insulating plate 46 is provided with a pair of spaced openings 64 and 65 and a pair of openings 66 and 67 are provided in the insulator 59 aligned with the openings 64 and 65 in the other insulator. Wires 68 and 69 are provided with hooks to engage the loop ends of the filaments 57 and 58 respectively and extend upwardly through holes 64 and 66, and 65 and 67 in the insulator 46 and the small insulator 59 respectively and may be attached to spiral springs 71 and 72 respectively. The springs 71 and 72 rest upon the top insulating plate 59 and support the filaments 57 and 58 under tension so that they cannot move with respect to the other elements.

In assembling the structure shown in Fig. 5 the three filament support posts 51, 52, and 53 may be inserted in their corresponding openings in the insulating plate 46 and the clips 54 placed in position and welded to the posts. Then the two filaments 57 and 58 may be welded between the posts 51 and 52, and 52 and 53 respectively and the wires 68 and 69 may be inserted through the openings to engage the loop ends of the two filaments. The small insulating plate 59 may be placed in position and the springs 71 and 72 placed thereupon and compressed whereupon the wires 68 and 69 are welded thereto. The anode and the grid may be placed in position upon the lower insulating plate and then the upper insulating plate with the attached filament supporting parts may be placed in position with the filament supporting posts assembled within the grid and protruding through the openings provided for that purpose in the lower insulating plate.

In order to mount the element unit thus formed upon the press 73, I provide two support rods 74 and 75 which extend through openings 76 and 77 in the insulating plates 46 and 47 and may be welded to the anode flanges 9 similarly to the posts 32 in the construction of Fig. 1. The posts 74 and 75, however, extend downwardly terminating a short distance below the lower insulating plate 47 and may be applied before the unit is positioned upon the press. A U-shaped yoke 76 may be provided below the insulating plate 47 and may be welded to the lower ends of the rods 74 and 75. Grooves 77 may be provided in the ends of the yoke for receiving the ends of the rods as indicated. Three support rods 78 may be sealed in the press 73 and spaced apart one in the center and the other at the extreme ends of the press. These rods may extend a short distance above the press and may terminate at the upper edge of the cross member 79 of the yoke which may be welded to these rods in order to secure the yoke and the attached element unit in position.

A second yoke 81 is provided below the insulating plate 47 and above the cross member 79 of the yoke 76 and has sufficient length to connect the lower ends of the grid support rods 16 and 17 to which the yoke may be welded. Grid connecting rods 82 are also provided sealed in the press and spaced just inside of the outer support rods 78. These support rods may be smaller than the support rods 78 and are somewhat longer extending up to the yoke 81 to which they may be welded.

Inside of the rods 82, I provide two filament connecting rods 83 which are spaced on each side of the center rod 78 and extend upwardly beyond the yoke 81 terminating at a point even with the lower end of the two outer filament support posts 51 and 53. Connectors 84 are provided to connect the upper ends of the filament rods 83 with the filament support posts 51 and 53 as clearly indicated in Fig. 5.

The yoke 76 may have offset portions 86 to clear the grid and filament support rods 82 and 83, as shown in Fig. 9, and the yoke 81 may have an offset portion 87 to pass around the filament connectors 83 as is also shown in Fig. 9.

The yoke 76 is connected to the anode 5 by means of the rods 74 and 75 and hence any one of the support rods 78 may be connected by means of a wire 88 to the anode terminal 89 at the base of the tube. The yoke 81 is connected to the grid by the grid support posts 16 and 17 and hence either one of the grid connectors 82 may

be connected by means of a wire 91 to the grid terminal 92 at the base of the tube. In like manner the filament connectors 83 which are connected to the filament posts 51 and 52 by means of the connector 84 may be connected by means of the wires 93 to the filament terminals 94 at the base of the tube.

This construction has the advantage that the support rods sealed in the press may be all straight and there need be no bending or cutting operation after the rods are positioned in the press but the whole element unit with the yokes attached may be laid against the support posts and welded to mount the unit in position.

In Fig. 10 a construction having an anode yoke and a grid yoke similar to the construction of Fig. 5 is shown and having a filament supporting mechanism similar to that shown in Fig. 1. The anode, grid, and the supports for the upper end of the filament protruding through the upper insulator are exactly the same as shown in Fig. 1 while the lower insulator 96 is provided with three straps 97, 98, and 99, spaced apart adjacent the center thereof. The straps pass completely around the insulator the ends coming together at the lower side of the insulator as indicated in Fig. 16 and being held in place by the natural stiffness of the metal. Each of the straps 97, 98, and 99 are provided with a lug 101, 102, and 103, respectively, under which the filament 104 is adapted to pass. Thus the filament may start at the lugs 101 on the strap 97, to which it may be welded, and pass upwardly over one of the hooks 31, down again under the lug 102 on the strap 98, up again over the other supporting hook at the top, and down again to be welded or to be otherwise secured to the lug 103 on the strap 99. In this manner the M-shaped filament is held in position, each portion thereof being maintained taut.

On the inner lower edges of the lugs 97 and 99, I provide fingers 106 and 107 respectively to which the upper end of the filament connectors 83 may be welded forming the filament connections for the tube.

The yoke 108 may be similar to the yoke 76 of Fig. 5 and the grid yoke 81 may be exactly similar to that shown in Fig. 5, the whole element unit being supported in exactly the same manner.

In place of the straps 97, 98, and 99, I may provide U-shaped clips 109, 110, and 111 (Fig. 17) which are spaced apart similarly to the straps 97, 98, and 99 but the ends of which are inserted in slots 112 formed in pairs in the lower insulator.

The ends of the U-shaped clips are bent under the underside of the insulating plate 113 as indicated in Fig. 18. The upper surface of each of the clips is preferably provided with a ridge or groove 114 similar to that shown at 26 in Fig. 4 to receive the filament. The insulator 113 may be provided with holes 115 and 116 just inside of the clips 109 and 111 respectively and the filament 117 may extend up through the hole 115, along the top surface of the insulator 113 and under the clip 109 engaging in the groove 114, then upwardly over one of the hooks 31, downwardly under the clip 110, upwardly again over the other hook 31, downwardly again and inwardly under the clip 111, and then downwardly through the hole 116 in the insulator 113.

The ends of the filament 117 extending below the insulator may be welded to the filament connecting rods 83 similarly to the fingers 106 and 107 shown in Figs. 10 and 16.

In Figs. 19 to 22 inclusive a further modification of the invention is shown which has an anode

and a grid similar to those shown in the other figures and an anode yoke and grid yoke similar to those shown in Figs. 5 and 10 and support rods sealed in the press in a similar manner to those shown in the last mentioned figures. A modified means for supporting the filament, however, is shown.

In this construction the upper insulating plate 118 is provided with a transverse slot 119 at its center through which a relatively narrow flat metal plate 120 extends. A clip 121 extends around the insulating plate 118 adjacent the flat plate 120 and has a slot 122 provided to receive the plate 120 which extends a short distance upwardly therethrough. The plate 120 extends downwardly to a point spaced slightly from the lower insulator 123. Between the lower end of the plate 120 and the insulating plate 123, I provide an insulating block 124 which is provided with a groove 126 at its central portion around which is placed a clip 127 whose sides extend upwardly a short distance adjacent the edges of the plate 120 to which they may be welded thus securing the plate 120 to the insulating block 124. Adjacent the ends of the insulating block 124, I provide grooves 128 around which clips 129 may be bent, the metal being stiff enough to remain fixed when once bent into place. A finger 131 is bent upwardly from each of the clips 129 and one end of each of these clips adjacent the center on the lower surface of the block 124 is bent downwardly forming a depending lug 132 which is adapted to engage in one of a pair of slots 133 provided in the lower insulator 123 spaced one on each side of the center.

The upper insulator 118 may be provided with two spaced openings 134 through which wires 136 having hooks on their lower ends may extend. A small insulating plate 137 may be provided to rest upon the clip 121 and may have a slot 138 at the center thereof to receive the upper end of the plate 120 which holds the insulator 137 in place upon the clip. Spaced holes 139 may also be provided in the insulator 137 to align with the holes 134 in the insulator 118 so as to receive the wires 136 which are extended therethrough. Coil springs 141 may be provided upon the insulator 137 and welded to the wires 136 to maintain a tension on the filament similarly to the construction previously described.

With this construction the plate 120 together with the block 124 may be mounted upon the upper insulator 118 and the filament 142 welded to the lug 131 on one of the clips 129, whence it may be brought upwardly over one of the hooks on one of the wires 136, then downwardly under the end of the plate 120, passing between the plate and the insulator 124, then upwardly over the hook on the other wire 136, and downwardly again to be welded to the lug 131 on the other clip 129. Thus the filament is completely supported upon the upper insulator 118.

In the assembly of the device the grid and anode may be attached to the lower insulator plate 123 and the upper insulating plate with the filament construction attached thereto may then be placed in position inserting the insulator 124 and plate 120 down inside of the grid with the lugs 132 engaging and passing through the openings 133 provided for that purpose in the lower insulator 123. When the parts are assembled in this manner the element assembly is similar to that shown in Fig. 5 and the filament connection may be made from the filament rods 83 to the depend-

ing FIGS 132 by means of connectors 84 similarly to the construction shown in FIG. 5.

It will be seen from the above description that I have provided a unitary element structure for an electron device in which the various parts are all rigidly secured in position with respect to each other and in which the assembly thereof may be accomplished easily and quickly and the whole structure mounted in the envelope upon the press with a minimum of operations.

Note should be made particularly of the construction shown in FIG. 1 in which all of the supporting wires sealed in the press help to support the element unit. Also the filament support posts form a means to position the element structure at a predetermined distance from the press and the lower insulator plate rests upon the posts. The construction lends itself particularly to use in which the device is subjected to severe vibration or jars.

Many modifications of the invention may be resorted to without departing from the spirit thereof and I do not desire to limit the invention to what has been shown and described except as such limitations occur in the appended claims.

What I claim is:

1. In an electron device a pair of spaced plates, supports for one of said plates, three metal straps secured to said supported plate, a pair of spaced hooks resiliently mounted upon said other plate, and an M-shaped filament supported between said plates and having the two upper loops of the M supported upon the two resiliently mounted hooks and the extreme lower ends of the M and the center loop thereof each being bound to said supported plate and plate supports by one of said straps.

2. In an electron device an insulating plate having a pair of spaced openings therein, a U-shaped conducting clip having legs extending through said openings, means on said clip to secure a filamentary cathode, said legs having semi-cylindrical extensions to form a socket for a support rod.

45 3. In an electron device a pair of spaced insulators, one of said insulators having three pairs

of spaced parallel slots, a U-shaped clip adjacent each pair of slots with its legs extending through said slots, said clips having semi-cylindrical legs to form sockets to receive supporting rods, an M-shaped filamentary cathode having its extreme ends attached to said two outer clips and the lower central loop attached to said center clip, and means to resiliently support the upper loops of said filament from said other insulator.

4. In an electron device a pair of spaced insulators, means for supporting said insulators, an electrode extending between said insulators and supported thereby, a filamentary electrode extending between said insulators, means to support said filamentary electrode resiliently upon one of said insulators, and means comprising metal straps for binding together said filamentary electrode, insulator supporting means, and supported insulator.

5. In an electron device an insulator, a support therefor, a filamentary electrode, straps binding together said support, insulator and displaced sections of said electrode, and means for supporting resiliently the displaced sections of said filamentary electrode.

6. In an electron device a pair of spaced insulators, a support for one of said insulators, a pair of straps secured in spaced relation to each other upon one of said insulators by surrounding a portion thereof, an M-shaped filamentary electrode extending between said insulators, each of said metal straps binding together an end of the filamentary electrode, the insulator supports, and the supported insulator, and means to resiliently support the loop end of said filamentary electrode upon the other insulator.

7. In an electron device a support, a plurality of wires sealed in said support, a lower insulation plate resting against the ends of some of said wires, an upper plate mounted on other of said wires, a filament mounted between said insulation plates, and a plurality of clips each binding a portion of the filament to the lower insulation plate and said plate to a wire end.

WALTER LOUIS KRAHL. 45
